UNITED STATES PATENT OFFICE.

FREDERICK C. KAINER, OF SOUTH HAVEN, MICHIGAN.

DISPENSING-MACHINE.

1,132,587.

Specification of Letters Patent. Patented Mar. 23, 1915.

Original application filed July 14, 1909, Serial No. 507,537. Divided and this application filed April 22, 1912. Serial No. 692,370.

To all whom it may concern:

Be it known that I, FREDERICK C. KAINER, a citizen of the United States of America, and a resident of South Haven, county of 5 Van Buren, State of Michigan, have invented certain new and useful improvements in Dispensing-Machines, of which the following is a specification.

The main objects of this invention are to 10 provide an improved mechanism for controlling the repetition of operations of a machine and particularly adapted for use in check controlled vending machines and other dispensing apparatus, wherein it is desirable 15 to have the machine perform a predetermined number of repetitions of a certain operation, as for instance, delivery of an article or package in a vending machine after the 20 operation of the machine has been initially started or made possible, for example, by the insertion of a coin into the machine; to provide a machine of this class which may be readily arranged or adjusted so as to change 25 the number of operations which the machine will automatically perform after having been started.

The present application is a division of my copending application, filed July 14th, 1909, Serial No. 507,537, in which application 30 claims are made covering features of the check controlled mechanism herein illustrated, but not particularly described and claimed.

A specific embodiment of this invention, 35 as applied to a check controlled cigar vending machine is shown in the accompanying drawings, in which:—

Figure 1 is a vertical section taken on the line A—A of Fig. 3, some of the adjacent 40 parts of the vending machine and its casing being omitted, and the parts being shown in their normal initial position, as when the machine is not operating. Fig. 2 is a similar section, taken on the line B—B of Fig. 3, 45 the moving parts being shown in relative positions which they occupy at one stage of the operation of delivering a cigar from the machine. Fig. 3 is a fragmentary top plan, showing the repeating mechanism and a portion 50 of the delivery mechanism, the coin chute being in section, and the inclosing casing being omitted. In this view, the gear trains of the spring motor are also omitted, in order to simplify the drawing. Figs. 4 55 and 5 are details illustrating different forms of counting wheels respectively designed to

cause the machine to deliver two or six cigars for each coin. Fig. 6 is a fragmentary detail in perspective, showing the controlling element, the catch which holds it in 60 operating position, and a portion of the mechanism which controls the tripping of the catch. Fig. 7 is an enlarged detail of the repeating mechanism, the parts being shown in the relative positions which they 65 occupy when the machine is stopped. Fig. 8 is a similar view, showing the relative positions of the parts when the machine is in the act of delivering a cigar, and when the repeating mechanism is in position to cause 70 the machine to continue to run after the delivery of the cigar. Fig. 9 is a similar view, showing the relative positions of some of the parts of the repeating mechanism which brings about the stopping of the machine 75 after the delivery of a cigar.

In general terms, the device illustrated in the drawings is a machine, specifically a cigar vending machine, driven by a motor arranged to normally produce a continuous 80 operation of the machine, but controlled by a controlling element which normally prevents the operation of the machine except for an interval of time after it has been retracted, as for example, in the specific construction shown, by means of the operation of coin controlled mechanism, and which is also provided with repeating mechanism arranged to cause the machine to perform a predetermined number of complete operations, specifically the successive delivery of 90 a predetermined number of cigars. The machine is also arranged in such manner that although its parts may operate in cycles, the completion of a cycle of operations 95 will affect the further operation of the machine only when conditions are such that the completion of such cycle results in the actual delivery of a cigar from the machine.

The device shown in the drawings includes a machine for vending cigars, a motor for operating said machine, check controlled mechanism comprising a controlling element normally urged into position for stopping the motor and adapted through the 100 presence of a coin or check in a certain position to start the motor, means actuated by a cigar during its delivery from the machine to cause the motor to stop, and repeating mechanism adapted to operate so as to count 105 the number of cigars delivered for each coin and prevent stopping of the machine until a 110

predetermined number of cigars have been delivered.

In the drawings, the vending machine is represented by the fragmentary portions 5 thereof which appear in the various views, the part 1 shown in Figs. 2 and 3 being a drum which delivers cigars singly and in succession from the magazine which is not shown.

10 The motor comprises a spring 3 and a suitable train of gears indicated in some of the views but omitted from Fig. 3 for the sake of clearness of the illustration.

One of the shafts 4 of the motor has 15 mounted upon it a fan 5 which, through its friction with the air, offers sufficient resistance to govern the speed of the motor. The stopping and starting of the motor is controlled by means of a controller element in 20 the form of a lever 6, pivotally mounted at 7 in the supporting frame and provided with a pin or shoulder 8 which is movable into and out of the path of the fan 5 through the movement of the lever 6 on its pivot. The 25 lever 6 is counterweighted so that it normally swings to position for stopping the motor. The lever 6 has an arm 9 which is bent at right angles near its end as illustrated in Fig. 3, and which carries at its end 30 a horizontally disposed plate or pin 10 which extends into position for receiving a coin from the coin chute 11.

Although the casing of the machine is not shown in the drawing, it will be understood 35 that the upper end 12 of the coin chute is adjacent and in line with a slot in the casing so that coins inserted into the slot will be conducted along the chute. Coins or checks which are of suitable form and material to 40 pass the coin detecting device will be delivered to the pan 10 and supported on edge upon said pan by the adjacent side walls of the coin chute. The counterpoise of the controlling element 6 is such that the weight 45 of a coin or check causes the pan 10 to descend, lifting the detent 8 from engagement with the fan 5 and causing the starting of the motor.

In order to permit the coin to be discharged 50 from the pan 10 and be forced into a display rack 13 where it can be seen by an attendant during the operation of the machine, there is provided a catch 14 which engages the arm 9 and retains it in its depressed position. This catch 14 is best seen 55 in Fig. 6 and the manner in which it engages the arm 9 will be understood from Figs. 8 and 9. The catch 14 is carried by a horizontal pivot 15, and is so disposed that 60 it falls by gravity to the limit of its movement to the left of Figs. 7, 8 and 9 when it is not in engagement with the arm 9. The mechanism for shifting the catch 14 into and out of engagement with the arm 9 comprises 65 a slotted arm 16 pivotally mounted on a stud

17 on a lever 18 which in turn is pivotally mounted at 19 on the supporting frame. The lever 18 has a forked arm which engages an eccentric 20 on one of the shafts of the motor so that the lever is caused to 70 oscillate while the motor is in operation. The catch 14 has an upwardly extending arm 21 which extends through the slot in the arm 16 and is bent at right angles at its upper end to prevent it from accidentally 75 slipping out of the slot.

The mechanism which causes the discharge of a check or coin from the pan 10 comprises a link or slide 22 which is pivotally connected at one end to the upper end 80 of the lever 18 and has at its other end a transversely extending shoulder 23 (Fig. 3), which extends into a horizontal slot 24 in one side of the coin chute 11. As the pivot 25 is farther from the pivot 19 than is the 85 pivot 17, the travel of the shoulder 23 is considerably greater than that of the arm 16, and during each oscillation of the lever 18, the shoulder 23 sweeps across the pan 10 so as to push off any coin which may be resting 90 thereon. A coin is shown at 26 in Fig. 3 in position on the pan. In order to keep the pan 10 in its depressed position until the catch 14 has engaged the arm 9, there is a dog 27 on the link 22 which prevents the 95 lifting of the pan until the lever 18 has returned to the opposite limit of its movement. During the travel of the coin ejecting link 22 toward the right of Fig. 3, one end of the slot in the arm 16 engages the arm 21 of the 100 catch 14 and pushes said catch into engagement with the arm 9 of the controlling element.

The cigar delivering mechanism is represented in the drawing by the pocketed drum 105 1, indicated in Figs. 2 and 3. An arm 28, rigid on a shaft 29, extends into engagement with the arm 16 and controls the elevation of said arm 16. This arm 28 is counterweighted so that it normally holds the arm 110 16 in the position in which it is shown in Fig. 7. When in this position, the arm 16 may push the catch 14 into engagement with the arm 9, but it cannot release said catch as the slot in the arm 16 is of such length 115 as to allow the arm 16 to travel back without releasing the catch.

The shaft 29 carries a pair of fingers 30 which extend into the path of cigars carried in the pockets of the delivery drum 1. When 120 these fingers 30 are engaged by a cigar 31 or other article which is being delivered by the machine as represented in Fig. 2 they are swung to one side so as to depress the arm 28 and allow the arm 16 to fall to a 125 suitable position for engaging the shoulder 32 on the arm 21 of the catch 14, as illustrated in Fig. 9. When arm 16 is in this position, it trips the catch and causes the instant stopping of the machine, since it re- 130

leases the controlling element and allows the pin 8 to block the rotation of the fan 5. In order to cause the machine to deliver a plurality of cigars for each suitable coin or check, there is provided a movable controlling member preferably in the form of a wheel 33, which is so located as to engage a shoulder 34 on the arm 16 and which is so shaped as to determine whether or not the arm 16 shall engage the shoulder 32 and trip the catch 14. In the form shown, the wheel 33 is a ratchet wheel having shallow and deep notches arranged in a predetermined order on its periphery. The shallow notches are of such depth that they support the arm 16 above the level of the shoulder 32, while the deep notches are of sufficient depth to allow the arm 16 to engage said shoulder 32. When the arm 28 is in its initial or normal position, it supports the arm 16 clear of the wheel 33 so that the reciprocating movement of the arm 16 has no effect upon the wheel. Whenever a cigar is being delivered, the contact of the cigar with the fingers 30 will depress the arm 28, and allow the shoulder 34 to engage the wheel 33. When in such position, each oscillation of the lever 18 causes the wheel 33 to be rotated through an angular interval corresponding to one tooth space of the wheel 33, there being a pawl 35, Fig. 1, which prevents reverse rotation of the wheel 33. The gearing of the motor should be such that the wheel 33 will be advanced through one such annular interval during the delivery of each cigar. If the wheel 33 is of the form shown in Fig. 4, that is, with alternately shallow and deep notches, then the machine will deliver two cigars for each coin delivered to the pan 10. If the wheel is of the form shown in Fig. 5, there will be six cigars delivered for each proper coin. By changing the arrangement of shallow and deep notches in the periphery of the wheel 33, any number of repetitions of the operation of the machine may be had.

The operation of the device shown is as follows:—The normal or initial position of all of the parts is shown in Fig. 1. When 50 a coin is inserted into the coin chute 11, if it passes the coin detecting devices, it will rest upon the pan 10 as indicated at 26 in Fig. 3, and through its weight will lift the detent 8 clear of the fan 5 and start the motor. The motor causes rotation of the delivery 55 drum 1 and operates the other feeding mechanism to cause cigars to be discharged one at a time as indicated in Fig. 2. The rotation of the motor also causes the lever 18 to oscillate, causing shoulder 23 on the link 22 to travel back and forth above the pan 10. During its movement to the right of Fig. 3, the lug 23 discharges the coin 26 and pushes it into the display rack where it may 60 be seen by an attendant. During the same

movement of the lug 23, the arm 16, through its engagement of the arm 21 of the catch 14, pushes said catch into engagement with the arm 9 of the controlling element 6 and prevents said element from returning to its 70 normal position after the discharge of the coin. If no cigar is in position to be delivered, the motor will continue to run, causing the drum 1 to rotate and causing the link 22 and the arm 16 to travel back and forth 75 in the manner described. During this operation, the arm 28 supports the arm 16 in such position that it cannot release the catch 14. As soon as a cigar, through contact with the fingers 30, withdraws the arm 28 80 from engagement with the arm 16, said arm 16 falls until its shoulder 34 engages the wheel 33. As the oscillation of the lever 18 is timed so as to make one complete forward and backward movement during the interval of time normally required to deliver one cigar, the wheel 33 will be rotated one tooth space for each cigar delivered. As the first cigar is delivered while the shoulder 34 is in engagement with a shallow notch in the 90 wheel 33, the wheel will prevent the arm 16 from tripping the catch. This movement will advance the wheel so that during the delivery of the next cigar the shoulder 34 will engage a deep notch in the wheel 33 95 and the arm 16 will accordingly be allowed to engage the shoulder 32 on the arm 21 and will therefore release the catch 14, causing the machine to come to a stop as soon as the link 22 has moved far enough to the left of 100 Fig. 10 to draw the dog 27 clear of the plate 10. It will thus be seen that the machine always stops with the mechanism in the normal initial position indicated in Figs. 1 and 7.

The copending application hereinbefore referred to describes and claims the features of the check controlled mechanism and feeding mechanism which are indicated in the drawings, but not described in detail nor 110 claimed in this application.

Although but one specific embodiment of this invention is herein shown and described, it will be understood that numerous details of the construction shown may be altered or 115 omitted, within the scope of the following claims, without departing from the spirit of this invention.

I claim:—

1. In a device of the class described, the 120 combination of vending mechanism, a motor for operating said mechanism, a controlling element movable between positions for stopping and starting said motor and adapted to be moved into position for starting the motor, a catch adapted to secure said controlling element in its starting position, a reciprocating part actuated by said motor and adapted to release said catch through the operation of the motor, and means adapted to prevent 125 130

said reciprocating part from engaging said catch and adapted to be retracted through a certain operation of said mechanism.

2. In a device of the class described, the combination of a motor, means initially holding said motor inactive, means for releasing said holding means, a movable counting member adapted when in one position to prevent said holding means from stopping the motor and adapted when moved to a certain other position to allow said holding means to stop the motor, ratchet teeth carried by said movable member, means for engaging said ratchet teeth to advance said member, vending mechanism driven by the motor, and means operated by said mechanism for causing said ratchet-engaging means to advance said counting member at each repetition of the operation of said mechanism.

3. The combination of vending mechanism, a motor adapted to operate said mechanism, means normally holding said motor inactive, mechanism for rendering said holding means ineffective to hold said motor, a counting wheel mounted to rotate and located in position to prevent the operation of said holding means when said wheel is in one position and to permit the operation of said holding means when said wheel is in a different angular position, ratchet means adapted to advance said wheel, and means operated by said mechanism for controlling said ratchet means.

35 4. The combination of a motor, means normally holding said motor inactive, means for releasing said holding means, vending mechanism driven by said motor, means operated by said mechanism for restoring said motor-holding means to holding condition, and means operated by said motor independently of said mechanism for delaying the operation of said restoring means, said delaying means being adapted to count the operations of the mechanism and to permit the operation of said restoring means when said motor has driven said mechanism through a predetermined plural number of operations.

50 5. The combination of a motor, means normally holding said motor inactive, means tending to restore said holding means to holding condition after it has been released, vending mechanism driven by said motor, means for preventing the restoration of said holding means to normal condition, said preventing means being rendered ineffective by the contact therewith of the article delivered by the mechanism upon each operation of said mechanism, and means arranged to count the operations of said mechanism and to delay the restoration of said holding means to normal condition until said mecha-

nism has delivered a predetermined number of the articles.

65 6. The combination of a motor, vending mechanism operated by said motor, means normally holding said motor inactive, means tending to restore said motor-holding means to holding condition, means operated by engagement with the article delivered by said mechanism and adapted to restore said motor-holding means to normal condition, and a counting member arranged to temporarily prevent the operation of said restoring means and to permit the operation of the same when mechanism has delivered a predetermined plural number of the articles.

70 7. The combination of a motor, means for starting the operation of said motor, mechanism operated by said motor, means operated by said mechanism for automatically stopping said motor and tending to stop the motor at each repetition of a certain operation of said mechanism, and means adapted to prevent the operation of said stopping means until said mechanism has performed a predetermined plural number of repetitions of said certain operation.

75 8. The combination of a motor, a controlling element normally urged into position for stopping said motor and adapted to be moved into position to permit the running of said motor, a catch adapted to secure said controlling element in position to permit the running of said motor, a reciprocating part actuated by said motor and normally urged into position for releasing said catch, supporting means adapted to prevent said reciprocating part from releasing said catch, vending mechanism operated by said motor and arranged to retract said supporting means upon each repetition of a certain operation of said mechanism, a counting member adapted to be engaged by said reciprocating part when said supporting means is retracted, said counting member being also adapted to prevent said reciprocating part from releasing said catch except when said counting member has been shifted a predetermined number of times, and ratchet means for shifting said counting member through successive operations of said reciprocating part while said supporting means is retracted by said mechanism, thereby causing the release of said catch upon the repetition of said certain operation of said mechanism a predetermined plural number of times.

80 Signed in Floyd county, Georgia, this 120 30th day of January, 1912.

FREDERICK C. KAINER.
